UNITED STATES PATENT OFFICE

JOHN MILTON JESTER, OF WASHINGTON, DISTRICT OF COLUMBIA

RELEASING CLAMP

Application filed September 20, 1928. Serial No. 307,138.

The invention relates to clamps intended to be used at the lower end of a string of insulators for supporting a conductor employed in high tension line service.

It is well known that in conducting high voltages for comparatively long distances it is customary to employ supporting towers at quite an appreciable distance apart, these towers being equipped with strings of insulators carrying some sort of clamp holding the conductor. Under variations in climatic conditions at different areas, and particularly at different sides of a mountain, foot-hill or the like, it frequently occurs that sleet or ice accumulates upon the conductor, resulting in a greatly increased weight which tends to pull to one side the string of insulators at a particular tower. This strain may, in actual practice, be so great as to topple over the tower or deform it in some respect. As the result of this condition which may exist and which has been frequently found to occur, I have devised the present invention which has for its general object the provision of a conductor supporting clamp which is capable of releasing the conductor upon the occurrence of an unusual strain upon one side thereof so that the conductor may slip through and permit the strains to become equalized or uniformly distributed.

An important object of the invention is to provide a clamp of this type which will maintain its holding action notwithstanding longitudinal movement of the conductor for a limited extent, it being a distinct feature that the clamp will not release the conductor until movement thereof has exceeded a certain predetermined amount.

Another object of the invention is to provide a suspension clamp having cam means for positively effecting separation of the clamping elements which normally engage the conductor so that no reliance need be placed upon the tension of the conductor or its tendency to resume a practically straight line position such as would be necessary under some circumstances or in connection with certain devices for this general purpose.

Still another object of the invention, and

an important one, is to provide a clamp which embodies the minimum number of parts, only three in fact aside from bolts and nuts, namely a suspension element and counterpart clamping members having coacting means thereon for certain purposes.

A still further object of the invention is to provide a conductor suspension clamp equipped with means whereby its tension or gripping action upon the conductor may be varied at the will of the installer, this means permitting adjustment to take up any wear which might occur after protracted use.

Yet another object is to provide a clamp which, if released upon the occurrence of an unusual strain, will be capable of resuming its grip or clamping action upon a conductor upon the cessation of the force operating to effect the initial release.

An additional object of the invention is to provide a releasing clamp of the character mentioned which will be very simple and inexpensive to manufacture, easy to install, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawings in which:

Figure 1 is a side elevation of a clamp constructed in accordance with the invention, showing it in its normal or cable gripping position or condition,

Figure 2 is an end elevation thereof,

Figure 3 is a central vertical cross sectional view,

Figure 4 is a side elevation showing a modification in which means is provided for adjusting purposes,

Figure 5 is a central vertical cross sectional view therethrough, and

Figure 6 is a fragmentary side elevation showing the means for preventing relative longitudinal movement of the clamping members.

Referring more particularly to the draw-

ings, I have shown the device as comprising a pair of complementary clamping members 1 and 2 which may be but which are not necessarily interchangeable. In other words it must be said at this point that these two members may be differently formed if desired though as a matter of convenience for manufacturing purposes they may be formed as counterparts. Each of these members is formed with a channeled seat 3 adapted to engage against the conductor 4 which may be stranded or otherwise, this detail being immaterial. Both of these members are somewhat elongated in actual practice and have flaring ends to avoid bringing any abrupt bending strains upon the conductor. In order to prevent relative longitudinal movement of these members, some means must be provided and in the present instance this means is shown as comprising lugs 5 on each member fitting between pairs of lugs 6 on the other. It is of course immaterial as to the exact arrangement of these lugs but by forming them in the particular locations disclosed it is apparent that the members 1 and 2 may be reversed end for end as may be found desirable in actual practice.

The suspension means is here shown as comprising a pair of links 7 adapted to be connected with the lowermost unit of a string of insulators regardless of the type thereof, these links being spaced apart at their lower ends so as to straddle the assembled members 1 and 2. Actually, these links are shown as apertured at their upper ends at 8 for engagement therethrough of a pin 9 connected with a clevis type of suspension means at the lower end of a string of insulators. However, other variations are readily apparent.

40 The invention contemplates the provisions of means, particularly cam means, whereby the members 1 and 2 will be held normally in clamping engagement upon the conductor 4 and also cam means for releasing this engagement upon the occurrence of an unusual strain at one side or the other of a string of insulators from which the clamp, and the conductor, may be suspended.

Even though quite a number of modifications might be suggested, it is preferable that the links 7 be provided, intermediate their ends, with laterally enlarged portions 10 formed with cam slots 11 for a purpose to be described. It is intended that the pair of links 7 be pivoted with respect to the lower clamping member 2 and I have therefore illustrated a bolt 12 passing through holes 13 in the links, through a hole 14 in the lower clamping member, and equipped with a single nut 15 which may be cottered or not, as found advisable.

In order to effect connection with the upper clamping member, I provide a bolt 16 which passes through a hole 17 in the upper clamping member 1 and through the cam slots 11,

this bolt being likewise cottered if preferred.

It should be pointed out that the cam slots 11 in the enlarged portions 10 of the suspension links are of peculiar shape inasmuch as each has a surface 18 concentric with the bolt 12 and other portions 19 which are reversely curved with respect thereto as clearly indicated in Figure 1, and also in Figure 4 though this latter figure will be hereinafter described in greater detail.

In the operation of the form of the invention disclosed in Figures 1 to 3 inclusive, it will be seen that installation of the clamp upon the conductor may be effected while the suspension links 7 are at an angular position with respect to the members 1 and 2 so that the bolt 16 will be at one end or the other of the cam slots 19. When this bolt 16 is in this position it will be apparent that there is no real clamping action exerted by the members 1 and 2 as they are then simply comparatively loose upon the conductor 4. When the links 7 are then subsequently swung into a position such that their vertical axis is at right angles to the longitudinal axis of the members 1 and 2, the bolt 16 is brought into engagement with the intermediate portion of the slot 11, and as this intermediate portion is concentric with the bolt 12 it is apparent that a firm clamping action upon the conductor 4 is obtained.

In service, it will be clear that if the clamp should move with the conductor to a limited extent at one side or the other of the vertical line through the string of suspension insulators, not shown, supporting the same, the bolt 16 will play over the intermediate portion 18 of each of the slots 11 in the suspension links, and nothing will happen. If, however, as the result of the accumulation of sleet or ice upon the conductor at one side of the string of insulators, or the tower supporting the same, there should be any tendency to pull the string laterally, the movement of the string of insulators and clamp or assembled clamping members with respect to the tower will result in bringing the bolt 16 into one end 19 or the other of the cam slot, as the case may be. When this occurs it is apparent that the coaction of the bolt 16 with either pair of end portions 19 of the cam slots will force the members 1 and 2 apart and permit the conductor 4 to slip through until an equilibrium in the conductor line at opposite sides of the tower, or string of insulators and clamp, is brought about.

The form of the invention disclosed in Figures 4, 5 and 6 is slightly different from what has been above described in a few particulars, especially in that means is provided for varying the degree of clamping action for taking up wear resulting from the inevitable movement of the parts.

Referring to these three figures in detail,

the numerals 21 and 22 represent the upper and lower clamping members channeled or otherwise formed to provide seats 23 for the conductor 24. Instead of having the lugs 5 and 6 arranged as in the first described form of the invention, the members 21 and 22 are shown as provided, each at one side, with a lug 25 received within a recess 26 in the other member. By this arrangement it will be apparent that the members 21 and 22 are interchangeable or reversible in the same sense as the members 1 and 2, the only difference being in the exact arrangement of cooperating lugs which prevent relative longitudinal movement of the members in service.

In the modification, the suspension means is shown as comprising a yoke 27 apertured at 28 and adapted for connection with a pin 29 or the like at the lower end of a string of insulators such, for instance, as by means of the pin 9 shown in Figure 2. Instead of considering the member 27 as a yoke connected at its lower end by the integral bight portion shown it might be construed as comprising a pair of links rather similar to the links 7 but rigidly connected at their lower ends in a manner equivalent to the integral bight. The sides of the yoke are formed intermediate their ends with cam slots 29 corresponding to the slots 19 for the passage of a bolt 30 corresponding to the bolt 16. As the members 21 and 22 are counterpart each is formed with a hole 31 so that regardless of which one is uppermost means is provided for the reception of the bolt 30. It should also be noted that the lugs 25 and recesses 26 at the opposite sides of the members 21 and 22 are alternately arranged so as to permit the reversal or interchangeable arrangement of the members 21 and 22. Of course these elements operate in the same manner as the lugs 5 and 6 of the first described form.

The means in this instance for effecting a positive engagement of the members 21 and 22 with the conductor, is shown as comprising a stud or set screw 32 which is threaded through the lower solid end of the yoke, or of whatever means connects the side of the yoke, and which has a preferably curved or spherical end 33 engaging within a recess 34. If the members 21 and 22 are made counterpart, which is of course not essential, it is intended that both be provided with a recess 34 so that either one may be the bottom.

In the operation of both forms it is apparent that the action is fundamentally the same inasmuch as the clamping members will be maintained in close engagement upon the conductor as long as the suspension means is in upright or only slightly inclined position with respect to the assembled clamping members. This is true owing to the fact that the center of the lower surface or wall or each of

the cam slots in the suspension links or yoke is concentric with the bolt 12 in one instance or the engagement of the set screw 32 within the recess 34 in the other instance. The second mentioned form of the invention has the advantage over the first form in that the set screw provides an adjustment not only for initially varying the degree of the clamping action but also for taking up any wear which might occur in the cam slots as the result of play of the string of insulators back and forth with respect to the clamping means. The material between the unoccupied hole 31 in the clamping member 32 and the recess 34 is sufficiently thick that there is no possibility of crushing through even though a very severe strain be applied. The lock nut shown at 35 in Figures 4 and 5 is simply for the purpose of preventing accidental unscrewing of the set screw.

From the foregoing description and a study of the drawings it will be apparent that I have thus provided a very efficient conductor clamp which will be positive in that no reliance is placed upon spring tension for either clamping or releasing purposes, a positive holding action and also a positive release being effected by cam action. Means has been provided for adjusting the grip and also for taking up any wear which, though unexpected and improbable, might by any chance develop. By making the clamping members counterpart it is apparent that the number of necessary parts will be reduced to the minimum, there being actually only three or four aside from the necessary bolts. On account of this extreme simplicity the cost of production should be very slight and as the parts do not have any relative movement under ordinary circumstances durability should be certain. It is believed that the construction, operation and advantages will be readily apparent to one skilled in the art without further explanation.

While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. A device of the character described comprising a plurality of clamping members adapted to be engaged upon a conductor, suspension means connected with said clamping members as an assembly, and cam slot means for maintaining the clamping members in clamping relation to the conductor.

2. A device of the character described

- comprising a plurality of clamping members adapted to be engaged upon a conductor, suspension means connected with said clamping members as an assembly, cam means for maintaining the clamping members in clamping relation to the conductor and means other than the tension of the conductor for moving the clamping members apart upon swinging of the suspension means with respect thereto.
10. 3. A device of the character described comprising a plurality of clamping members adapted to be engaged upon a conductor, suspension means pivotally connected with said members, cam means cooperating with the suspension means and clamping members for maintaining the clamping relation, and other cam means operative upon swinging movement of the suspension means with respect to the clamping means for releasing the latter.
15. 4. A device of the character described comprising a plurality of clamping members adapted to be engaged upon a conductor, suspension means pivotally connected with said members, cam means cooperating with the suspension means and clamping members for maintaining the clamping relation, and other cam means operative upon swinging movement of the suspension means with respect to the clamping means for releasing the latter, said clamping members being reversible and interchangeable.
20. 5. A device of the character described comprising a plurality of clamping members adapted to be engaged upon a conductor, suspension means pivotally connected with said members, cam means cooperating with the suspension means and clamping members for maintaining the clamping relation, and other cam means operative upon swinging movement of the suspension means with respect to the clamping means for releasing the latter, said clamping members being counterparts.
25. 6. A device of the character described comprising a plurality of clamping members adapted to be engaged upon a conductor, suspension means pivotally connected with said members, cam means cooperating with the suspension means and clamping members for maintaining the clamping relation, other cam means operative upon swinging movement of the suspension means with respect to the clamping means for releasing the latter, and cooperating means formed on the clamping members for preventing relative longitudinal movement thereof and guiding the same during release thereof.
30. 7. A device of the character described comprising a plurality of clamping members adapted to be engaged upon a conductor, suspension means pivotally connected with said members, cam means cooperating with the suspension means and clamping members for maintaining the clamping relation, other

cam means operative upon swinging movement of the suspension means with respect to the clamping means for releasing the latter, and means on the clamping members for preventing relative longitudinal movement thereof, said last named means operating also to guide said clamping members during separating movement and comprising interfitting lugs.

8. A device of the character described comprising the combination of a plurality of clamping members adapted for engagement upon a conductor, suspension means pivotally connected with one of the clamping members, and cam means connecting the suspension means with the other of said clamping members for normally maintaining the clamping members in clamping relation to the conductor and for forcing them apart upon the occurrence of relative swinging movement of the suspension means and clamping means beyond a predetermined extent.

9. A device of the character described comprising a plurality of clamping members adapted for engagement upon a conductor at the top and bottom thereof, suspension means straddling both clamping members and pivoted to the lower one thereof, cam means on the suspension means, and means projecting laterally beyond the upper clamping member cooperating with said cam means for normally maintaining the clamping members in clamping relation to the conductor.

10. A device of the character described comprising the combination of a plurality of clamping members adapted for engagement upon a conductor, suspension means pivotally connected with one of the clamping members, cam means connecting the suspension means with the other of said clamping members for normally maintaining the clamping members in clamping relation to the conductor, means other than the conductor for forcing the clamping members apart for rendering them ineffective upon the occurrence of relative swinging movement of the suspension means and clamping means beyond a predetermined extent, and means for adjusting the clamping members relatively to each other to vary the grip on the conductor.

11. A releasing clamp comprising upper and lower clamping members adapted for engagement upon a conductor, suspension means straddling both clamping members and including spaced arms, a pivot element passing through the lower portions of said arms and through the lower clamping member, a transverse element carried by the upper clamping member, and said arms being formed with cam slots cooperating with said transverse element for normally maintaining

the clamping members in clamping relation to the conductor.

12. A releasing clamp comprising upper and lower clamping members adapted for engagement upon a conductor, suspension means straddling both clamping members and including spaced arms, a pivot element passing through the lower portions of said arms and through the lower clamping member, a transverse element carried by the upper clamping member, and said arms being formed with cam slots cooperating with said transverse element for normally maintaining the clamping members in clamping relation to the conductor and for forcing them apart upon movement of the suspension means beyond a predetermined position with respect thereto, said cam slots having portions concentric with said pivot element to maintain the clamping relation throughout limited movement of the suspension means.

13. A releasing clamp comprising upper and lower clamping members adapted for engagement upon a conductor, suspension means straddling both clamping members and including spaced arms, a pivot element passing through the lower portions of said arms and through the lower clamping member, a transverse element carried by the upper clamping member, and said arms being formed with cam slots cooperating with said transverse element, said cam slots having curved portions concentric with the pivot element coacting with said transverse element for maintaining the clamping action of the clamping members throughout limited relative movement of the clamping members and suspension means and having other portions curved oppositely for coaction with the transverse element to force the clamping members apart upon relative movement of the suspension means and clamping members beyond a predetermined relative position.

14. A releasing clamp comprising upper and lower clamping members adapted for engagement upon a conductor, suspension means straddling both clamping members and including spaced arms, a pivot element passing through the lower portions of said arms and through the lower clamping member, a transverse element carried by the upper clamping member, said arms being formed with cam slots cooperating with said transverse element for normally maintaining the clamping relation of said clamping members upon the conductor and for releasing the clamping action upon relative movement of the suspension means and clamping members beyond a predetermined extent, and means carried by the suspension means and engaging the lower clamping member for adjusting the same with respect to the upper clamping member.

15. A releasing clamp comprising upper and lower clamping members adapted for en-

gagement upon a conductor, a suspension yoke straddling both clamping members and rockably supporting the lower one thereof, each clamping member having a recess and a projection whereby the recesses and projections will cooperate to prevent relative longitudinal movement of the clamping members, coacting means on the yoke and upper clamping member for normally holding said clamping members in clamping relation upon the conductor, and cam means on the yoke and upper clamping member for forcing the clamping members apart upon the occurrence of swinging movement of the yoke with respect thereto beyond a predetermined extent.

16. In a releasing clamp, upper and lower clamping members adapted for engagement upon a conductor, a suspension yoke straddling the clamping members and having a closed lower end or bight portion, means extending through said bight portion constituting a fulcrum for the lower clamping member, and cam means on the yoke and upper clamping member operating normally to maintain the clamping members in clamping relation upon the conductor and also operable to force the clamping members apart.

17. In a releasing clamp, upper and lower clamping members adapted for engagement upon a conductor, a suspension yoke straddling the clamping members and having a closed lower end or bight portion, means extending through said bight portion constituting a fulcrum for the lower clamping member, and cam means on the yoke and upper clamping member operating normally to maintain the clamping members in clamping relation upon the conductor and also operable to force the clamping members apart, said fulcrum means being adjustable for moving the lower clamping member with respect to the upper independently of the action of said cam means.

18. A suspension clamp device, comprising clamping members engageable upon a conductor, suspension means for the clamping members, and cam means connecting the suspension means and the clamping members for normally maintaining the latter in clamping relation to the conductor and for positively moving them apart upon relative movement of the suspension means and clamping means beyond a predetermined extent.

In testimony whereof I affix my signature.
JOHN MILTON JESTER.
